UNITED STATES PATENT OFFICE.

HOWARD F. MAXIM AND GEORGE F. PERHAM, OF LOCKE MILLS, MAINE.

GARMENT-SUPPORTER.

1,320,486.

Specification of Letters Patent.

Patented Nov. 4, 1919.

Application filed September 17, 1918. Serial No. 254,441.

To all whom it may concern:

Be it known that we, HOWARD F. MAXIM and GEORGE F. PERHAM, both citizens of the United States, residing at Locke Mills, in the county of Oxford and State of Maine, have invented certain new and useful Improvements in Garment-Supporters, of which the following is a specification.

The invention has relation to suspenders and garment supporting means of analogous nature wherein engaging devices such as hooks, pins, and the like are employed together with straps, tapes, and like connecting means, the purpose being the provision of an engaging device for coöperation with an eye, said engaging device having an enlarged laterally yieldable portion which is compressed when passed through the eye and which automatically expands after passing through the eye to prevent casual disengagement or unfastening of the attaching device.

The primary purpose of the invention is the provision of a hook of special formation embodying a bill having an expanded portion which is laterally yieldable, said hook being designed for coöperation with a part having one or more eyelets for the reception of the bill portion of the hook.

Specifically considered, the invention relates more particularly to suspenders or garment supporting means and to the attaching devices whereby the supporting means may be readily engaged with and quickly disengaged from the part to be connected.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

In the drawings:

Figure 1 is a detail view in an elevation of a suspender end and waist band of a garment showing one application of the invention.

Fig. 2 is a detail view of the hook in elevation showing the link associated therewith, such link being in cross section.

Fig. 3 is a sectional view on the line 3—3 of Fig. 1 showing the parts on a larger scale.

Fig. 4 is a front view of a modification.

Fig. 5 is a sectional detail on the line 5—5 of Fig. 4 showing the parts on a larger scale.

Fig. 6 is a further modification.

Corresponding and like parts are referred to in the following description and indicated in the several views of the drawings 60 by like reference characters.

The fragmentary portion of a pair of suspenders illustrated in Fig. 1 comprises a shoulder strap 1, a suspender end 2, and intermediate connecting means, such as a link 65 3 and cast-off 4. These parts are of well known construction and are illustrated simply to demonstrate the application of the invention.

The numeral 5 designates a waist band or 70 like part of a garment the same being provided with tabs 6 which are stitched thereto at their lower ends. Each of the tabs 6 is provided with a plurality of eyelets 7 which may be of usual formation and applied to 75 the tab in any well known manner. In Fig. 4, the eyelets 7 are applied directly to the waist band 5 or like part, said waist band having a single eyelet for each of the hooks attached to the suspender end. In Fig. 6, 80 80 the waist band 5 or like part is provided in its length with a plurality of eyelets 7, whereby provision is had for engaging the hooks of a suspender end at varying points 85 in the length of the waist band or like part. It will thus be understood that the suspenders or like supporting means may be attached directly to the waist band or to tabs or like means applied to the waist band.

The essential feature of the invention re- 90 sides in the hook, irrespective of its manner of application, said hook being shown most clearly in the enlarged views—Figs. 2, 3, and 5, the same comprising the usual parts such as the shank, bight, and bill. In the 95 present instance, the shank of the hook consists of an elongated open frame comprising spaced members 8 which have their upper ends inturned, as indicated at 9 so as to engage a link 10 of any well known construc- 100 tion. The lower ends of the members 8 are brought together to form the bight 11 of the hook. The shank of the hook is flat and by having the same constructed in the manner illustrated, it presents a substantially broad 105 surface to hold the hook in a given position. The bill 12 of the hook comprises spaced elements which are symmetrically curved in opposite directions, as indicated at 13, to form a widened or laterally expanded part 110 which constitutes a guard to prevent casual disengagement of the hook from an eyelet

when in engagement therewith. The widened or laterally expanded portion 13 of the bill is laterally yieldable so as to be reduced in width when passing the bill of the hook through an eyelet or similar opening, such portion 13 automatically expanding for clearing the eyelet to prevent accidental withdrawal of the bill through the eyelet. The end portion of the bill curves toward the plane of the shank as indicated most clearly in Figs. 3 and 5 with the result that the part 5 or 6 disposed between the shank and bill of the hook is held in a manner to prevent displacement and so as to keep the part 5 or 6 flat and prevent its wrinkling or forming into a welt.

The members 8 of the shank may extend parallel as indicated most clearly in Fig. 2, or they may be upwardly divergent as illustrated in Fig. 6, the purpose being to provide a part of sufficient extent for engagement with the link 10 or suspender end 2. In Fig. 4 the links 10 are shown connected directly with the hooks, whereas in Fig. 6, the suspender end 2 has direct connection with the hooks. In the formation of the hook, the same is constructed of a single length of spring wire of suitable gage, such wire being doubled upon itself at a central point and bent into the form substantially as illustrated. It will thus be understood

that the hook is light, strong, and durable and possesses a certain amount of resiliency to compensate for strain.

It will be understood from the foregoing, 35 that the invention provides attaching means well adapted for garment supporters, and that in the practical adaptation thereof, the hook may be secured by means of its shank to any part, whereas the bill of the hook 40 may engage with the remaining part to be coupled. Thus the application may be the reverse of that illustrated, as will be readily comprehended.

What we claim is:

45 In garment supporting means, a hook embodying a shank comprising spaced elements having their terminal portions inturned and coming together to be engaged within a link or like part, and having its bill comprising spaced elements which at a point in their length are oppositely and symmetrically curved to form a laterally yieldable widened portion constituting a guard.

50 In testimony whereof we affix our signatures in presence of two witnesses.

HOWARD F. MAXIM.
GEORGE F. PERHAM.
